UNITED STATES PATENT OFFICE.

ERNEST EMMEL SCHMID, OF JAMAICA, NEW YORK.

DESIGN FOR A STRAIN-INSULATOR.

43,342.

Specification for Design.

Patented Dec. 10, 1912.

Application filed January 26, 1912. Serial No. 673,701. Term of patent 14 years.

To all whom it may concern:

Be it known that I, ERNEST EMMEL SCHMID, a citizen of the United States of America, residing in Jamaica, Long Island, county of Queens, State of New York, have invented a new, original, and ornamental Design for Strain-Insulators, of which the following is a specification, reference being had to the accompanying drawing, forming part thereof.

In the one sheet of drawings, Figure 1

illustrates top view of my strain insulator; Fig. 2 is a side view thereof; Fig. 3 is a front view thereof showing my new design.

I claim:

The ornamental design for a strain insulator as shown.

ERNEST EMMEL SCHMID.

In the presence of—

EDW. VAN WINKLE,
M. E. McLEAN.
